UNITED STATES PATENT OFFICE.

FRANK DUTCHER, OF VERSAILLES, PENNSYLVANIA, ASSIGNOR TO CENTRAL RAILWAY SIGNAL COMPANY, OF PITTSBURGH, PENNSYLVANIA, A CORPORATION OF NEW JERSEY.

RAILWAY SIGNAL-TORPEDO.

1,200,323.

Specification of Letters Patent.

Patented Oct. 3, 1916.

Application filed October 8, 1915. Serial No. 54,875.

To all whom it may concern:

Be it known that I, FRANK DUTCHER, a citizen of the United States, residing at Versailles, in the county of Allegheny and 5 State of Pennsylvania, have invented certain new and useful Improvements in Railway Signal-Torpedoes, of which the following is a specification, reference being had therein to the accompanying drawing.

10 This invention relates to improvements in railway signal torpedoes and particularly pertains to that class in which there is a bulged central portion to receive the explosive compound, and two turned flaps 15 which are closed over and cemented to the flange of the bulged portion and to the explosive compound.

The object of my present invention is to so construct a torpedo of the type here 20 shown that the rail-engaging strap serves to lock and hold the flaps in position, and the flaps assist in holding the rail-engaging strap.

In the accompanying drawings, Figure 1 25 is a perspective view of my improved torpedo looking at the under side thereof. Fig. 2 is a cross sectional view of the torpedo showing it applied to a railroad rail. Fig. 3 is an inverted plan view of the torpedo. 30 Fig. 4 is a perspective view showing the parts of the torpedo in separated relation.

The torpedo case comprises a central portion 1 which is shaped to form a cavity 2 to receive a tablet compound 3. This central portion 1 has an annular flange 4 and this annular flange 4 is provided with integral oppositely arranged flaps 5. As shown each of the flaps 5 is of a size about equal to half the size of the bottom of the central 40 portion 1 and its flange 4. The explosive tablet 3 is placed in the cavity 2 and surrounded by suitable waterproof cement 6. A disk 7 is placed over the tablet and is of a size to fit and correspond with the size 45 and shape of the central portion 2 and its flange 4, and it is cemented thereto.

The flaps 5 are provided with strap receiving openings 8 and when the flaps are in a partially inwardly folded position a rail-engaging strap 9 is threaded through these 50 openings and the flaps are then completely folded and cemented to the disk 7. A second disk 10 is provided with strap receiving openings 11, and the ends of the strap are

turned outward at right angles to the torpedo and in parallel positions, and the said second disk 10 is placed in position on the folded flaps with the strap 9 threaded through the openings 11 and the disk cemented in this position.

From the foregoing it will be seen that the flaps 5 are held by the strap 9, and the strap 9 is held by the flaps and by the disk 10, the parts when united serving to make a substantial and efficient construction, the pull of the strap being substantially parallel to the bottom of the torpedo when applied to the rail; as shown in Fig. 2 the pull will not serve to separate the flaps or the disk.

Having thus fully described my invention what I claim and desire to secure by Letters Patent is:

1. An improved railway signal torpedo comprising a casing having a central portion with an explosive receiving cavity, a surrounding flange and oppositely arranged inwardly folding flaps, an explosive tablet within the cavity, each of the flaps having a strap opening so located that they are out 75 of register when the flaps are folded and a rail engaging strap passing through the openings of the two flaps.

2. A railway signal torpedo having a case composed of a central portion having an explosive tablet receiving recess, an annular flange, and integral inwardly folding flaps, a disk placed over the cement, the flaps folded inwardly over the disk, an outer disk placed over the flaps, the outer disk and the 80 flaps having strap receiving openings, a strap passing through the openings, the flaps and the disks being cemented together and to the central portion.

3. An improved railway signal torpedo, 85 comprising a casing having a central portion with an explosive receiving cavity, a surrounding flange, and oppositely arranged inwardly folding flaps, each flap being of a size approximately half of the size of the 90 central portion and its flange, each flap having a strap opening so located that they are out of registry when the flaps are folded, and a rail engaging strap threaded through the openings.

4. An improved railway signal torpedo comprising a casing having a central portion with an explosive receiving cavity, a

surrounding flange and oppositely arranged inwardly folding flaps each of a size about equal to half the size of the central portion and its flange, an inner disk over the explosive, the flaps each having a strap opening, an outer disk, and a rail engaging strap threaded through the openings of the flaps.

Copies of this patent may be obtained for five cents each, by addressing the "Commissioner of Patents, Washington, D. C."

In testimony whereof I hereunto affix my signature in the presence of two witnesses.

FRANK DUTCHER.
